Patented Feb. 23, 1915.

UNITED STATES PATENT OFFICE.

WILLIAM S. TRASK, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

SASH CENTERING AND HOLDING MEANS.

1,129,530.

Specification of Letters Patent. Patented Feb. 23, 1915.

Application filed May 4, 1914. Serial No. 836,125.

To all whom it may concern:

Be it known that I, WILLIAM S. TRASK, a citizen of the United States, residing at New Britain, Hartford county, State of Connecticut, have invented certain new and useful Improvements in Sash Centering and Holding Means, of which the following is a full, clear, and exact description.

My invention relates to an improved centering and holding device for transoms and the like.

The object of the invention is to provide a very effective and durable means of the character described.

It is a further object to provide an effective means for adjusting the tension of the holding means.

In the drawings, Figure 1 is a view of the rear side of my improved sash centering and holding device. Fig. 2 is an edge elevation. Fig. 3 is a cross section through the center. Fig. 4 is a view of one of the parts detached. Fig. 5 is a view of the other of the parts detached. Fig. 6 is a perspective view of one of the details of construction.

The centering device includes two hinged members pivotally connected. In this instance 1 represents a pivot, central with the hub 2 of one of the hinged members.

3—3 are arms on the hub 2, said arms being arranged to be secured, as by screws, to the transom sash or to the casing. The other member includes a hub portion 4 having a central passage for the pivot and having one or more arms 5—5 which may be secured to the transom sash or casing. The arms 3—3 and 5—5 are diagonally disposed so that all the arms may be swung into substantial parallelism, as shown in solid lines, Fig. 1, or may be swung into the position indicated by dotted lines, representing the position of the sash relatively to the casing when the sash is open.

Many devices have been employed for frictionally retaining sash centering devices in different positions, but owing to the fact that such parts should be very powerfully retained to overcome the pressure of heavy drafts of air and to prevent rattling, the wear of such parts as heretofore constructed has been very rapid, resulting in quickly rendering the devices inefficient. My improved construction comprehends an improvement whereby there is great resistance to wear. The retaining means com-

prises an annular plate 6 mounted in a correspondingly shaped recess in the hub 2 and surrounding the pivot 1. Any suitable means may be provided to prevent the plate 6 from turning, for example, the plate may have lugs 7—7 which stand in offset recesses in said hub. In the exposed face of the plate 6 and arranged concentrically, are a series of closely arranged notches 8—8. In the hub 4 are a plurality of guide passages which are preferably provided with steel bushings 9—9 in which are located balls 10—10. The overall diameter of the balls 10—10 is preferably in excess of the thickness of that part of the hub in which they stand, for the reasons hereinafter explained. The balls 10—10 are located at such a distance from the center of the hub 4 as to register with the notches 8—8.

11 is a steel spring washer plate designed to fit over the pin 1 and stands at the back of the hub 4. This spring plate 11 is so formed as to provide at its periphery spring arms 12—12, said arms preferably being curved to follow the outline of the edge of the plate 11. These arms are provided in a number corresponding to the number of balls 10—10 employed, in this instance four. The plate 11 is so applied that a spring arm 12 will rest upon and press against a ball 10 so as to force said ball against the steel plate 6 and so that it will be pressed into that one of the notches therein in line therewith. The spring plate 11 may be provided with any suitable means to prevent the plate from becoming angularly dislodged, thereby maintaining the correct positioning of the spring arms 12 and the complementary balls 10. In this instance the spring plate 11 is provided with lugs 13—13 which take into notches or recesses in the hub 4 adjacent to the recess in which the plate is located. The pivot stud or bolt 1 is screw-threaded and may be provided with an adjusting nut 14 which may draw down against the spring plate 11 so as to vary the degree of pressure of the spring arms 12 against the balls 10.

15 is a lock nut.

The notched plate 6, the spring plate 11, the balls 10—10 and the bushings 9—9 should be hardened sufficiently to resist wear.

When the parts are assembled, the spring arms 12—12 will force the balls 10—10 into the notches 8—8 to thereby restrain the two

members from turning unless sufficient force is applied to overcome the tension of the springs. When sufficient tension is applied, the two parts to which the two hinged members are connected may be moved relatively to each other to the desired angle, that is to say, when the parts are in place, the transom may be pushed to a closed position, or pulled open to the desired angle so that in whatever position it is left said transom will be securely held against being swung or rattled by drafts of air.

It is obvious that in supporting a transom there must be a pivot at each supporting point. Each end bearing of the transom may be provided with a duplicate means, such as described herein, or only one of said bearings need be provided with such a centering and holding means, the other bearing being plain. It is also obvious that the plate 6 is in reality a part of the hub 2, although it is preferably formed of hardened steel instead of a material having a lesser wear-resisting capacity. Broadly speaking, therefore, said plate 6 is part of the hub 2, and in some instances, in the event the hub 2 were made of steel for example, the plate and the hub portion could be integral, such a modification being too obvious to require illustration. So, also, if the hub 4 were made of steel or the like, the bushings 9—9 might be omitted.

What I claim is:

1. In a sash centering and holding means, two hubs mounted concentrically, a series of notches in the face of one hub, a plurality of ball passages through the other hub arranged to register with said notches in the

first mentioned hub, balls in said passages, and means carried at the back of the second mentioned hub for applying pressure to said balls to force them into the notches of the first mentioned hub, said means comprising a steel washer plate including spring arms, with means for forcing said plate into engagement with the balls so as to vary the pressure against the balls.

2. In a sash centering and holding means, two hubs mounted concentrically, a series of notches in the face of one hub, a plurality of ball passages through the other hub arranged to register with said notches, balls in said passages, a spring plate carried by the second mentioned hub at the back of said balls, and pressing against a plurality of the latter with means to hold said plate against rotation relatively to said second mentioned hub.

3. In a sash centering and holding means, two hubs mounted concentrically, a series of notches in the face of one hub, a plurality of ball passages through the other hub arranged to register with said notches, balls in said passages, a spring plate carried by the second mentioned hub at the back of said balls, and pressing against a plurality of the latter with means to hold said plate against rotation relatively to said second mentioned hub, and with means for adjusting the pressure of said spring plate against said balls.

WILLIAM S. TRASK.
